CARL H. BISSELL, OF SYRACUSE, NEW YORK, ASSIGNOR TO CROUSE-HINDS COMPANY,
OF SYRACUSE, NEW YORK, A CORPORATION OF NEW YORK.

ELECTRIC FLASHER SWITCH MECHANISM.

Application filed February 26, 1925. Serial No. 11,738.

This invention relates to an electric flasher, and has for its object a rotary switch mechanism and motor therefor, which is particularly simple and economical in construction, and highly efficient and durable in use.

The invention consists in the novel features and in the combinations and constructions hereinafter set forth and claimed.

In describing this invention reference is had to the accompanying drawings in which like characters designate corresponding parts in all the views.

Figure 1 is an elevation of this flasher, the casing being partly broken away, and also a portion of the rotor of the motor being broken away.

Figure 2 is a plan view of the flasher, the case being removed.

Figure 3 is an elevation looking to the right in Fig. 2.

Figure 4 is a sectional view on line 4—4, Fig. 2.

Figure 5 is a detail sectional view on line 5—5, Fig. 2.

Figure 6 is a fragmentary inverted plan view of the base.

This electric flasher comprises generally a unit consisting of a motor of the disk type, and a rotatable electric switch connected to the disk. The flasher in its entirety, comprises a base of insulation, a secondary base mounted on the former base and supporting the motor and the switch mechanism, and a cap or cover resting on and enclosing the base of insulation.

1 designates the base of insulation which is mountable upon any suitable support as the base of an automatic traffic signal or so-called silent policeman.

2 designates the secondary base, this being mounted upon the base 1 and secured thereto in any suitable manner. The base 2 is of any suitable form, size, and construction.

3 designates the magnet of an induction disk motor, and 4 the coils thereof, the magnet 3 being mounted flatwise on the base 2 and secured thereto in any suitable manner as by screws 5.

6 is the disk forming part of the rotor of the motor, this disk being mounted on a shaft 7, suitably supported in bearings 8 provided in uprights 9 on the base 2, the bearings 8 being here shown as threading through the uprights 9 and formed with conical sockets for receiving the conical ends

10 of the motor shaft 7. The disk 6 is arranged with a portion thereof on one side of its axis moving between the poles of the magnet 3.

The switch mechanism comprises a rotary 60 switch member, in contra-distinction to an oscillating switch member, connected to the rotor or the motor shaft 7 to be actuated thereby. The switch member includes a receptacle partly filled with a fluid conductor, 65 as mercury, a pair of terminals carried by the receptacle and arranged to move into and out of the mercury during rotation of the receptacle, and conductors including wires connected to the pair respectively and to other 70 parts which rotate with the receptacle and with which coat brushes connected in the circuit controlled by the switch.

The construction is such that the wires or conductors connected to the pair of terminals 75 do not have any flexing or twisting strain, as in oscillating mercury switches.

11 designates the receptacle which is an annular glass tube, and 12 the mercury or fluid conductor partly filling the receptacle 80 11. The receptacle is carried by a shaft extending cross-wise of the shaft 7 and connected thereto through intermeshing gears, as a worm 13 on the shaft 7, and worm gear 14 on the switch shaft. This switch shaft 85 is composed of sections 15, 16, arranged end to end, and insulated from each other, the section 15 being journaled in an upright 17 rising from the base 2, and the section 16 journaled in a similar upright, these 90 uprights being provided with bearings for the sections 15, 16, similar to the bearings 8 for the shaft 7. The bearing for the section 15 is insulated from the upright by a bushing 17a. As here shown one section of the shaft, as the section 15, is formed with an enlargement 18 having a bushing 19 of insulation therein, and the inner end of the section 16 has a bearing in such bushing of insulation. The sections 15, 100 16, are coupled together by means of a metallic disk 20 on the section 16 and fixed thereto to rotate therewith and an annular flange 21 on the bushing 19, the flange abutting against the disk 20, and the disk 20 being secured thereto as by screws 22. The annular receptacle is carried by the disk 20 concentric with the shaft sections 15 and 16, and is here shown as secured to the disk 20 by clamping means as clips 23 secured to the disk 20, and 105 110

hooking around the receptacle 11. A suitable washer of felt or any other cushioning material 24 is inserted between the receptacle 11 and the disk 20.

5 A pair of terminals are located at spaced apart points in the wall of the receptacle 3 in order to be submerged in the mercury during the rotation of the receptacle so that the circuit is closed across these terminals 10 when both are submerged in the mercury.

25 and 26 designate the terminals of a pair of terminals carried by the receptacle 11 and extending onto the interior thereof in order to dip into and out of the mercury during 15 the rotation of the receptacle. Preferably there are two pairs of terminals 25, 26, located diametrically opposite each other. It will be evident that but one pair of terminals are submerged at any one time.

20 27 is a terminal in the form of a disk on the shaft section 15, and 28 is a similar terminal on the shaft section 16.

25 29 and 30 are brushes coacting with said terminals 27, 28, respectively, and connected in the electric circuit to be opened and closed by the rotation of the terminals 25, 26, through the mercury. The brush 29 is carried by the bearing for the shaft section 15, and is formed U or V-shaped for providing 30 spring tension to force the brush against the coacting disk terminal 27. One arm of the brush is bifurcated to straddle the shaft section 15 and bear on the disk terminal 27 on opposite sides of the shaft section 15. The bearing to which the brush 29 is connected is 35 provided with a binding device 31 at its outer end for connection to the line wire 32. The brush 30 is in the form of bifurcated flat spring carried by the upright 17, for pressing 40 against the disk terminal 28.

This brush 30 is grounded through the base 2 to the line wire 33. Each terminal 25 of the pair of terminals 25, 26, is connected by a wire 34 to a binding device 35 on the shaft section 15 and each terminal 26 is connected by a wire 36 to a binding screw 37 on the disk 20, so that, each terminal 25 is in circuit with the disk terminal 27, and each terminal 26 is in circuit with the disk 50 terminal 28 and brush 30 through the disk 20 and shaft section 16.

When both terminals 25, 26, of either pair are submerged in the mercury, the circuit from the brush 29 to the brush 30 is closed 55 and the lamp or lamps connected in circuit with the wires 32, 33, are flashed. The wire 33 is connected to a binding device 39 on the bottom of the base 1. The binding device

31 is also connected to another binding device 40 on the bottom of the base 1 by the 60 wire 32, and the service and load circuit wires are connected to the binding devices 39 and 40.

The opposite ends of the coils 4 of the magnet are connected respectively to the 65 binding device 39 and a binding device 41 which is connected in the feed circuit. Also the binding device 41 may be connected in a load circuit containing a light that is permanently illuminated and not flashed. 70

The switch and motor mechanism is enclosed in a case or cap 42 resting at 43 on the margin of the base 1 and having a skirt 44 enclosing the base 1, this skirt having an opening 45 for the circuit wires. 75

For the purpose of oiling the antifriction conical bearings of the motor and switch shafts a pad saturated with oil is mounted on the base 2, the oil vapor from this pad serving to lubricate the bearings. 80

In operation when the circuit is closed through the feed wires by a suitable manually operated switch, the motor rotates and in turn rotates or tumbles the switch member or the receptacle 11 continuously in one direction, thus alternately opening and closing the load circuit and causing the lamp or lamps to flash at regular intervals. 85

What I claim is:-

1. An electric flasher comprising a rotatable switch member including an annular receptacle of insulation having a fluid conductor partly filling the same, means for rotating the switch member, a pair of terminals exposed in the receptacle, wires connected at like ends to the terminals respectively and at their other ends to conductors rotatable with the switch members, the wires being rotatable with the switch member and brushes coacting with the conductors of the switch member. 95

2. A rotary electric switch comprising a shaft composed of two sections insulated from each other, a carrier mounted on one of the sections, an annular receptacle for a fluid conductor supported by the carrier, a pair of terminals mounted in the receptacle, wires connecting the terminals respectively and the shaft sections and brushes coacting with the sections respectively. 105

In testimony whereof, I have hereunto signed my name, at Syracuse, in the county of Onondaga and in the State of New York, this 9th day of February, 1925.

CARL H. BISSELL.
